Patented Dec. 27, 1966

206,520

MOTOR OPERATED TOOTHBRUSH HANDLE

Jerold R. Peterson, Roselle, Ill., assignor to Sunbeam Corporation, Chicago, Ill., a corporation of Illinois

Filed June 29, 1966, Ser. No. 2,865

Term of patent 14 years

(Cl. D9—2)

Fig. 1

Fig. 2

Fig. 3

Fig. 4

Fig. 5

FIG. 1 is a front perspective view of a motor operated toothbrush handle embodying my new design;

FIGS. 2 and 3 are side and rear elevational views respectively thereof; and

FIGS. 4 and 5 are top and bottom plan views respectively thereof.

The dominant features of my design reside in the portions shown in full lines.

I claim:

The ornamental design for a motor operated toothbrush handle, as shown and described.
